UNITED STATES PATENT OFFICE.

OTTO JOHNSON, OF JAMESTOWN, NEW YORK.

CURTAIN ROD.

Application filed February 17, 1923. Serial No. 619,728.

To all whom it may concern:

Be it known that I, Otto JOHNSON, a citizen of the United States, residing at No. 71 Pershing Avenue, Jamestown, in the county 5 of Chautauqua and State of New York, have invented certain new and useful Improvements in Curtain Rods, of which the following, taken in connection with the accompanying drawings, is a specification.

10 This invention relates to an improvement in curtain rods and more particularly to means for supporting the same.

The chief object of this invention is to provide an inexpensive and efficient means 15 for mounting the curtain rod upon the casement whereby the rod can be quickly mounted and dismounted and whereby the weight of the rod functions to hold it in the mounted position.

20 Other objects will appear from an examination of the specification taken in connection with the drawings which form a part thereof and in which

Figure 1 is a front elevation of a casement 25 equipped with a curtain rod embodying one form of this invention.

Fig. 2 is a bottom plan view of the casement and curtain rod.

Fig. 3 is a fragmentary end of the curtain 30 rod illustrating the position it assumes when mounted for supporting the curtain.

Fig. 4 is a view similar to Fig. 3 showing position of the rod when being disengaged from the supports; and

35 Fig. 5 is a further view showing another position of the rod while being removed from the support.

Referring to the drawings the reference numeral 10 is used to designate a casement 40 provided with a curtain rod 11 embodying a form of this invention. The rod here shown is of the well-known extensible type, the ends 12 of which are bent at right angles so that the curtain supporting portion 13 45 is mounted in front of and parallel to the casement 10. At each end are provided loops 14 by which the rod is suitably supported.

Brackets 15 preferably of a single piece, as here shown, are employed to support the 50 ends of the rod. Bracket 15 is preferably made in the form of a hook from a rod or heavy wire having one end 16 bent at right angles to the body of the hook and pointed so that it can be driven into the casement 55 like a nail. The hook is coiled at 17 at the inner end of the portion 16 to stiffen it so

that it can be driven like a nail into the casement and also to provide further resilience to the hook for the purpose set forth hereinbelow. The lower end of the bracket 15 is 60 bent upwardly to form a pocket 18 and terminates adjacent the casement. Referring particularly to Figs. 3 and 4 it will be noted that when the end 16 is driven into the casement the tip 19 will lie against the casement 65 and be held in that position both by the natural tendency of the hook and by the additional resilience imparted by the coiled portion 17.

The loops 14 of the rod 11 are made of 70 sufficient size so that they can pass over the doubled lower end of the hook 15, as shown in Fig. 5. When in functioning position the lower edges of the loops 14 lie in the pockets 75 18 and are normally held in that position both by the weight of the curtain and by the tendency of the bracket to lie with the tip 19 against the casement, as shown in Fig. 4.

When the curtain rod is dismounted it is 80 not necessary to remove the brackets 15 from the casement but the rod is lifted as indicated in Fig. 4 until the lower ends of the loops 14 are above the tips 19 of the bracket. The curtain rod is then swung into the horizontal position and the loops 14 are pulled down over the tips 19, as shown in Fig. 5, until free of the brackets. The curtain rod is, of course, mounted upon the brackets by 85 reversing this procedure. 90

While only one embodiment of this invention has been shown and described, it is obvious that others can be made without departing from the spirit and scope of the invention as set forth in the following 95 claims.

Having thus set forth my invention what I claim as new and for which I desire protection by Letters Patent is:

1. The combination with a casement of a 100 curtain rod having loops at each end and brackets fixed to said casement said brackets having vertical pockets open at the top at the lower ends and so formed that said curtain rod can be mounted upon said brackets 105 by passing the loops of said rod over the lower ends of the brackets until above the pockets and then lowering the loops into said pockets.

2. The combination with a curtain rod 110 having loops at each end of supporting hooks therefor, each of said hooks having its

lower end bent back upon itself to form a pocket, the tip of said hook being adjacent to the casement to which the hook is secured and forming the inner wall of said pocket and the loops of said rod being of such dimensions that they can pass over the doubled lower end of said hooks and so placed in said pockets.

3. An integral supporting hook for a curtain rod consisting of a pointed upper por-

tion at right angles to the body portion, a coiled portion at the inner end of said pointed portion, and a lower end bent back upon the body portion to form a pocket the mouth of which is on the same side of the body as the pointed portion.

In testimony whereof I have affixed my signature.

OTTO JOHNSON.
